SET OF TICKTACKTOE GAME PEGS OR
SIMILAR ARTICLE

Gordon E. Kaye and Herbert Jacobel,
Westchester County, N. Y.

Application October 12, 1953, Serial No. 27,142

Term of patent 7 years

(Cl. D34—5)

Fig. 1

Fig. 2

Fig. 3

Fig. 4

Fig. 1 is a top perspective view of one of the two pegs in a set of ticktacktoe game pegs or similar article, showing our new design;

Fig. 2 is a bottom perspective view of the peg shown in Fig. 1;

Fig. 3 is a top perspective view of the other peg in the set; and

Fig. 4 is a bottom perspective view of the peg shown in Fig. 3.

The design relates to a set of ticktacktoe game pegs characterized by a design motif comprising a relatively low cylindrical base, a portion extending radially outwardly at the upper portion of the base and an upper cylindrical handle portion of less diameter and greater height than the base.

We claim:

The ornamental design for a set of ticktacktoe game pegs or similar article, as shown and described.
